ATTORNEY

UNITED STATES PATENT OFFICE

ERNESTO DAMI, OF NEW YORK, N. Y.

SHOE FORM

Application filed April 23, 1929. Serial No. 357,418.

This invention relates to new and useful improvements in shoe form.

The invention has for an object the provision of a device of the class mentioned which is of simple durable construction, dependable in use and efficient in action, and which may be manufactured and sold at a reasonable cost.

The invention proposes an integral vamp and toe portion held in spaced relation to a heel portion by a spring steel strap, said spaced relation being arranged adjustable for accommodating shoe of various lengths. The vamp and toe portion may be modified to have edge sections pivotally connected to the main portion thereof and urged into spread positions by coaxial spring so as to tension the toe and vamp portion of a shoe when the toe is engaged therein.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a side elevational view of a device constructed according to this invention.

Fig. 2 is a bottom view thereof.

Fig. 3 is a vertical sectional view taken on the line 3—3 of Fig. 2.

Fig. 4 is a fragmentary side elevational view of a portion of Fig. 1, but disclosing a modified form.

Fig. 5 is a bottom elevational view of the portion shown in Fig. 4.

Fig. 6 is a transverse vertical sectional view taken on the line 6—6 of Fig. 5.

The reference numeral 10 indicates generally an integral vamp and toe portion made of sheet metal preferably aluminum and having curved and inturned bottom edges 11. A guide member 12 provided with an enlarged base 13 is supported within the portion 10 and preferably is made from spring steel. The guide member has a rear tongue 14 for engaging in one of a plurality of apertures 15 formed in a spring steel strap 16.

This strap is slidably mounted in the guide member 12 and has a slightly down turned front end 17 preventing complete disengagement of the strap from the guide member. The rear end of the strap 16 is turned at right angles to the main portion as indicated by reference numeral 18 and is attached upon a heel portion 19. This heel portion is made from sheet metal preferably aluminum and has curved and inturned bottom edges 20.

In Figs. 1 and 2, the dot and dash lines 21 indicated a shoe into which the shoe tree has been engaged. In engaged position the strap 16 is slightly bowed for firmly forcing the vamp and toe portion 10 of the device into the front portion of the shoe and the heel portion 19 against the back portion of the shoe. It should be noticed that the heel portion 19 is at a material higher elevation than the vamp and toe portion 10 for corresponding with the usual construction of shoes.

The operative length of the shoe tree may be adjusted for engagement into shoes of different sizes by holding the vamp and toe portion 10 and pushing forward on the strap 16 so that the tongue 14 disengages from the aperture 15. The strap 16 may then be slid into a new position in the guide 12 and the tongue reengaged in one of the said apertures 15 for holding the parts in their new positions. Dot and dash lines 22 in Fig. 2 indicate the heel portion 19 in a complete retracted position, that is, with the strap 16 completely engaged thru the guide member 12. In this condition of the device it takes up a minimum quantity of room and may be conveniently stored away while not in use.

In the modified form of the device illustrated in Figs. 4, 5 and 6, a vamp and toe portion 10' has been shown consisting of a main central portion 23 and edge sections 24 hingedly connected with the main portion as at 25. Coaxial springs 26 are arranged upon the hinge axis of the edge sections and are arranged for normally urging the edge sections into expanded position as indicated by the dot and dash lines 27 in Fig. 6. Rear extensions 28 project from the rear portions of the sections 24 and serve as handles which may be manually pressed together.

while the vamp and toe portion 10' is inserted within the shoe upon releasing, the springs 26 act to expand the sections 24 tensioning the toe and vamp portion of a shoe and tending to eliminate wrinkling therein.

5 While I have shown and described the preferred embodiment of my invention, it is to be understood that I do not limit myself to the precise construction herein disclosed and 10 the right is reserved to all changes and modifications coming within the scope of the invention as defined in the appended claims.

Having thus described my invention, what 15 I claim as new, and desire to secure by United States Letters Patent is:—

1. A shoe form, comprising a vamp and toe portion, a guide attached thereon, a strap engaged in the guide, a heel portion attached on the rear of the strap, said vamp and toe 20 portion having edge sections hingedly mounted and urged into spread conditions by springs coaxial on the hinges, and rear extension members projecting from the rear of the edge sections for allowing manual forcing of the 25 edge sections together while inserting and removing the vamp and toe portion from a shoe.

2. A shoe form, comprising a vamp and toe portion, a guide attached thereon and having a rearward projecting tongue, a strap 30 engaged in the guide and having apertures engageable by the tongue, and a heel portion attached on the rear of the strap, said strap having a bent forward end arranged for preventing complete disengagement of the strap 35 from the guide.

3. A shoe form, comprising a vamp and toe portion, a guide attached thereon, a strap engaged in the guide, and a heel portion attached on the rear of the strap, said vamp and 40 toe portion having edge sections hingedly mounted and urged into spread conditions by springs coaxial on the hinges.

In testimony whereof I have affixed my signature.

45 ERNESTO DAMI.
